Term of patent 14 years

(Cl. D44—29)

FIG.1

FIG.2

FIG.3

FIG.4

FIG.5

FIG.6

FIG.7

FIGURE 1 is a perspective view of holder for electrically powered knife or the like showing my new design;

FIGURE 2 is a front elevational view of the same;

FIGURE 3 is a side elevational view of the same on one side;

FIGURE 4 is a side elevational view of the same on the opposite side;

FIGURE 5 is a rear elevational view of the same;

FIGURE 6 is a top plan view of the same; and

FIGURE 7 is a bottom view of the same.

The broken line showing of a motorized knife handle in FIGURE 3 is for illustrative purposes only.

The broken lines in FIGURES 2 and 3 indicate a driving unit for the knife and cutting blades therefor carried by the holder.

I claim:

The ornamental design for a holder for electrically powered knife or the like, as shown and described.
